UNITED STATES PATENT OFFICE.

CHARLES L. ALLEN, OF SALT LAKE CITY, UTAH, ASSIGNOR TO UTAH PATENT AND IMPLEMENT COMPANY, OF SALT LAKE CITY, UTAH, A CORPORATION OF UTAH.

LAY-OFF AND PULVERIZING MACHINE.

1,160,120.

Specification of Letters Patent.

Patented Nov. 16, 1915.

Application filed August 19, 1914. Serial No. 857,491.

To all whom it may concern:

Be it known that I, CHARLES L. ALLEN, citizen of the United States, residing at Salt Lake City, in the county of Salt Lake and State of Utah, have invented new and useful Improvements in Lay-Off and Pulverizing Machines, of which the following is a specification.

My invention pertains to ground-working machines; and it consists in the peculiar and advantageous lay-off and pulverizer herein-after described and definitely claimed.

In the accompanying drawings, which are hereby made a part hereof: Figure 1 is a plan of the machine constituting the best practical embodiment of my invention that I have as yet devised. Fig. 2 is a longitudinal vertical section, taken in a plane at the left of the driver's seat and looking toward the right hand side of the machine. Figs. 3 and 4 are detail views showing the arrangement of the plows relative to the shoe, and the connection of the plows to the shoe.

Similar numerals of reference designate corresponding parts in all of the views of the drawings.

Among other elements my novel machine comprises a concavo-convex shoe 1 for smoothing the ground. Connected with and carried by the said shoe is an attachment similar to that shown in the B. F. Luke Patent #923,057 of May 25, 1909, and made up of arms 2 fixed on and extending rearwardly from the shoe, a rock-shaft 3 journaled in said arms and bearing harrow teeth 4 and a hand lever 5, the latter equipped with a detent 6 to engage a segmental rack 7 on one of the arms 2, and wheels 8, loosely mounted on the rock-shaft.

Arranged below the shoe 1 and in front of and in alinement with the wheels 8 are plows 9. These plows are identical in construction and therefore a detailed description of the one shown in Figs. 2, 3 and 4 will suffice to impart a definite understanding of both. The plow referred to comprises a body having a forward tapered portion 9' and a rear channel-iron portion 10 on the side walls of which are abutments 11 that bear solidly against the rear edge of the shoe 1; a V-shaped point 12 resting at the sides and in front of the forward end of the body and fixed thereto, and a blade 13 fixed to the forward end of the body and the point 12 and extending upwardly and rearwardly

therefrom. The blade 13 is provided at its upper end with a reduced portion 14 that extends through an aperture 15 in the shoe 1. This blade serves the twofold function of bracing the forward end of the body and the point 12 from the shoe 1, and assists the abutments 11 in holding the plow in proper relation to the shoe 1. At 16 and 17 the plow is provided with threaded bolts. These extend upwardly through the shoe 1 and are equipped with nuts 18, through the medium of which the plow is held snug against and is connected with the shoe. It will be noticed in this connection that when necessary either plow can be expeditiously and easily removed from the shoe and as readily replaced with a new plow. It will also be noticed the channel-iron portions 10 of the plows are alined with and receive the forward portions of the wheels 8.

Manifestly the arrangement of the blades 13 in the apertures of the shoe and between the shoe and the plow body and the point, coupled with the arrangement of the abutments 11 against the rear edge of the shoe, and the bolt and nut connection between the bodies and the shoe, renders the connection of the plows to the shoe stiff and strong, all strain being taken off the bolts and the plows being adapted to be removed from the shoe as soon as the nuts are taken off the bolts.

The plows are adapted incidental to the operation of the machine to cut furrows, while the shoe serves to smooth the earth raised by the plows, and the wheels finish the furrows or contribute to the proper formation thereof by pressing into the walls any clods that may roll into the furrows. When the ground is damp and the shoe smooths the same to a too great extent, the harrow teeth may be used to break up the ground and thereby prevent baking of the surface thereof.

Fixed to and rising from the rear portions of the shoe 1 is a standard 20 on which is a driver's seat 21. Also fixed to rising from the shoe 1, though at a point near the forward edge thereof is a loop-shaped upright 22. In this upright is disposed and movable the rear reduced end 23 of the tongue 24 which is pivoted at 25 between braces 26 that are fixed to and extend forwardly and inwardly from the shoe.

Carried by and rising from the shoe 1 is a segmental rack 30 and short standards 31,

and journaled in said rack and standard is a rock-shaft 32. At its ends beyond the standards 31 the said rock-shaft is provided with cranks 33 having axles 34 on which ground wheels 35 are loosely mounted and suitably secured. Fixed to the shaft 32 is a hand lever 36, equipped with a detent 37 arranged to seat in the interdental spaces of the racks 30.

10 It will be readily observed that because of the provision of the rock-shaft 32, and its appurtenances, the machine may be moved on the wheels 35 when not in use; also, that the provision of the rock-shaft and the 15 wheels takes the weight entirely off the necks of the horses while the machine is in use as well as while it is being moved from one field or point to another. Moreover by manipulating the hand lever 36, the operator is enabled to set the wheels and regulate the depth of the furrows, and is also enabled to regulate the pressure of the shoe or plate 2 on the ground so as to avoid pressing the surface more than is necessary. From this 25 latter it follows that the provision of the cranked shaft and its appurtenances renders the draft of the machine very light.

It will further be manifest from the foregoing that incidental to the operation of the 20 machine, the tongue is left free, and hence the transmission of vibration to the necks of the draft animals is avoided.

Having described my invention, what I 25 claim and desire to secure by Letters-Patent, is:

1. In a machine of the kind described, the combination with a shoe; of plows arranged under and against and bolted to the

shoe and respectively comprising a body having a forward tapered portion and a rear channel-iron portion on the side walls of which are abutments that bear against the rear edge of the shoe, a point fixed with respect to the forward portion of the body, and a blade fixed to and extending upwardly 45 from the forward portion of the body and point and having its upper portion disposed in an aperture in the shoe.

2. In a machine of the kind described, the combination of a shoe, plows arranged 50 under and against the shoe and fixed with respect thereto, a standard rising from the rear portion of the shoe and equipped with a driver's seat, standards rising from the shoe near the ends thereof, a segmental-rack 55 fixed on the shoe, a shaft journaled in said standards and provided beyond the same with cranks on which are journals, wheels mounted on said journals, a lever fixed on said shaft and having a detent to engage 60 said rack, tongue-supporting means fixed to and extending forwardly from the shoe, a vertically swinging tongue pivoted at an intermediate point of its length to said supporting means, and means on the shoe receiving the rear end of the tongue and constructed and arranged to limit upward movement of said end.

In testimony whereof I have hereunto set my hand in presence of two subscribing 70 witnesses.

CHARLES L. ALLEN.
